UNITED STATES PATENT OFFICE.

WILLIAM H. FULPER, OF FLEMINGTON, NEW JERSEY.

DESIGN FOR A LAMP SHADE OR SIMILAR ARTICLE.

Application filed May 5, 1922. Serial No. 2,105. Term of patent 3½ years.

To all whom it may concern:

Be it known that I, WILLIAM H. FULPER, a citizen of the United States of America, and resident of Flemington, in the county of Hunterdon and State of New Jersey, have invented a certain new, original, and ornamental Design for Lamp Shade or Similar Article, of which the following is a specification, reference being had to the accompanying drawing, forming part thereof.

In the drawing, the figure is a perspective view of a lamp shade embodying my design.

I claim:

The ornamental design for a lamp shade or similar article, as shown.

WILLIAM H. FULPER.
